CLAIM

The ornamental design for a manifold, as shown and described.

DESCRIPTION

Cross-reference is made to U.S. Design patent application Ser. No. 29/713,833, titled "Manifold," filed on the same day as the present application, all of which is expressly incorporated herein by reference.

FIG. 1 is an upper perspective view of a manifold showing our new design;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1; and,

FIG. 8 is a lower perspective view of the design of FIG. 1. The broken lines shown in the drawings are included for the purpose of illustrating the unclaimed boundary and unclaimed portions of the manifold. The broken lines form no part of the claimed design.
